[57] CLAIM

The ornamental design for a telephone stand or similar article, substantially as shown and described.

DESCRIPTION

FIG. 1 is a top plan view of a telephone stand or similar article embodying our new design;

FIG. 2 is a side elevation thereof, the opposite side being essentially a mirror image of the side shown;

FIG. 3 is a bottom plan view thereof;

FIG. 4 is an end elevation thereof;

FIG. 5 is an end elevation of the opposite end from that shown in FIG. 4; and

FIG. 6 is a perspective view thereof.

FIG. 1

FIG. 2

FIG. 3

FIG. 5

FIG. 4
